ATTORNEY.

UNITED STATES PATENT OFFICE

122,723

DESIGN FOR A SURGICAL ILLUMINATING UNIT OR SIMILAR ARTICLE

John A. Korengold, Chicago, Ill.

Application June 24, 1940, Serial No. 93,207

Term of patent 3½ years

To all whom it may concern:

Be it known that I, John A. Korengold, a citizen of the United States, residing at the city of Chicago, county of Cook, State of Illinois, have invented a new, original, and ornamental Design for a Surgical Illuminating Unit or Similar Article, of which the following is a specification, reference being made to the accompanying drawing, forming a part thereof, in which Figure 1 is a top plan view, Figure 2 is a side elevational view, and Figure 3 is an end elevational view of a surgical illuminating unit or similar article embodying my new design.

The supporting member represented in broken lines in Fig. 2 has been omitted from Figs. 1 and 3 for convenience of illustration.

The dominant features of my design reside in the portions represented in full lines.

I claim:

The ornamental design for a surgical illuminating unit or similar article, substantially as shown and described.

JOHN A. KORENGOLD.
